US00D616675S

(12) United States Design Patent
Lowsky

(10) Patent No.: US D616,675 S
(45) Date of Patent: * Jun. 1, 2010

(54) TABLE

(76) Inventor: Jamie Lowsky, 7000 Island Blvd., Apt. 106, Aventura, FL (US) 33160

() Term: 14 Years

(21) Appl. No.: 29/343,816

(22) Filed: Sep. 18, 2009

(51) LOC (9) Cl. 06-03

(52) U.S. Cl. D6/488

(58) Field of Classification Search D6/480-489, D6/495-499, 511, 429-431; 108/150, 153.1, 108/155, 156, 157.1, 161; 248/188, 188.1, 248/188.8

See application file for complete search history.

(57) CLAIM

The ornamental design for a table, as shown and described.

DESCRIPTION

FIG. 1 is a perspective view of my ornamental design; FIG. 2 is a top plan view of the ornamental design of FIG. 1; FIG. 3 is a bottom plan view of the ornamental design of FIG. 1; and,

FIG. 4 is a right side elevation view of the ornamental design of FIG. 1; and,

FIG. 5 is a left side elevation view of the ornamental design of FIG. 1.

The broken lines in FIG. 1 and FIG. 3 are shown for the purpose of illustrating a portion of the table that forms no part of the claims design.

1 Claim, 4 Drawing Sheets
